UNITED STATES PATENT OFFICE.

JACOB PATOSKA, OF MASCOUTAH, ILLINOIS.

COMBINATION LOCK.

Application filed July 1, 1920. Serial No. 393,324.

To all whom it may concern:

Be it known that I, JACOB PATOSKA, a citizen of the United States, residing at Mascoutah, in the county of Saint Clair and State of Illinois, have invented certain new and useful Improvements in Combination Locks; and I do hereby declare the following to be a full, clear, and exact description of the invention, such as will enable others skilled in the art to which it appertains to make and use the same.

This invention relates to new and useful improvements in locks and more particularly to permutation padlocks, the primary object of the invention being to provide a device of this character which cannot be picked thereby providing substantially a burglar-proof lock.

A further object of the invention resides in providing a lock consisting of few and simple parts which may be quickly and readily assembled or disassembled for the purpose of changing combinations.

A still further object resides in providing a device which is simple and inexpensive to manufacture, and one which will be extremely efficient in use.

With these and other objects in view, my invention consists in the novel features of construction, combination, and arrangement of parts as will be hereinafter referred to, and more particularly pointed out in the specification and claims.

In the drawings forming a part of this application,

Figure 1 is a plan view of the invention,

Figure 2 is a view thereof principally in vertical section,

Figure 3 is a transverse section through the same,

Figure 4 is an elevation of the shackle removed, and

Figure 5 is a perspective view of one of the tumblers removed.

In describing the invention, I shall refer to the drawings in which similar reference characters designate corresponding parts throughout the several views, and in which 1 designates a shell or casing for my improved lock, said shell or casing consisting of a bottom plate 2, vertical side walls 3, the latter being preferably formed integral with the plate 2, and a top plate 4 which is separable from the side walls 3, to which the same is secured. The bottom plate 2 is provided with a pair of openings

5 and the top plate 4 is similarly provided with openings 6 in alinement with the openings 5. Mounted in these openings 5 of the bottom plate and riveted or otherwise 60 similarly secured therein are the tubular stems or barrel members 7. These barrel members 7 are provided with longitudinal slots or key-ways 8 and the upper ends of said barrel members are engaged within the 65 openings 6 of the top plate 4. These openings 6 are provided with lateral slots or key-ways 9 and the barrel members 7 are so arranged between the top and bottom plates 2 and 4 that the key-ways or slots 70 8 register with the key-ways or slots 9.

It is not necessary that the top plate 4 be secured permanently to the side walls or any other portion of the shell or casing 1 but if desired, it may be so connected. It is 75 preferable, however, that said top plate 4 be removably engaged with the side walls of this shell or casing so that the device may be readily disassembled. In this manner, it will, therefore, not be necessary to 80 permanently engage the upper ends of the barrel members 7 within the openings 6 of the top plate 4. However, it will be understood that it is within the scope of the claims of this invention to permanently 85 secure the barrel members to the top plates.

Loosely mounted on the barrel members 7 between the top and bottom plates of the shell or casing are a plurality of hexagonal tumblers 9'. In the drawings, I have shown 90 four such tumblers on each barrel member, but it will be understood that any number of tumblers may be provided, as desired. On each face of the hexagonal tumblers 9' is inscribed a number and also inscribed thereon is a mark or indentation designated in the drawing as 10. These indentations 95 10 just mentioned are adapted to register in vertical alinement with an indentation 11 on each side of the top plate 4, as will 100 be described in detail herebelow in connection with the operation of the lock.

Each of the tumblers with the exception of the lower faces of the lowermost of each series on the barrels 7 is provided also with 105 a slot or key-way 12 communicating with the central opening thereof as is clearly illustrated in Figure 5 of the drawings. These slots or key-ways 12 are adapted to register with the slots or key-ways 8 of the 110 barrels 7 when the lock is to be opened as will be hereinafter described.

A shackle 13 is provided, the arms 14 of which are formed by the offsetting of said shackle at points indicated as 15. The arms 14 have inwardly projecting and spaced 5 apart lugs 16 formed thereon. These lugs are shown as integral with the arms 14 but it will be understood that they may be constructed separable therefrom so that in the event of damage to any one or more of the 10 lugs, the same may be replaced readily. These lugs projecting inwardly, as described, are adapted upon the application of the shackle to the body of the lock to register with the key-ways and slots of the openings 15 and barrels heretofore described and upon the movement of the tumblers in any other position than the registration referred to, the shackle could not be introduced to the lock nor could the same be removed there- 20 from.

In describing the operation of this lock, it will, for convenience, be assumed that the lock is in its assembled and locked position, that is, the shackle properly engaged with 25 the tumblers in the lock body.

This being a permutation lock, there is a particular position of each tumbler predetermined in order to open the device, and each tumbler is therefore rotated on each of 30 the barrels until the predetermined number has been indicated. This indication is represented by the number facing outwardly from the lock body so that the indentation on the face of the tumbler corresponding with 35 that number registers with and alines with the indentation 11 on the top plate 4 of the body of the lock. When all tumblers have been rotated to the desired and predetermined positions for opening the lock, it is 40 only necessary to withdraw the shackle 13 with a hard pull from the body. It will be understood that by the turning of the tumblers 9' to a predetermined position that the

slots or key-ways 12 thereof will register with the slots 8 of the barrels 7 allowing the 45 lugs 16 of the shackle 13 to be readily withdrawn through these alining key-ways.

From the foregoing, it will be seen that I have provided a simple, inexpensive and efficient means for carrying out the object of 50 my invention.

It will be understood also that while I have described specifically the various features of the invention that various changes may be made therein within the scope of the 55 appended claim.

What I claim as new is:—

A permutation lock having a casing provided with a bottom wall and side walls integral with the bottom wall and being unobstructed at the ends, said bottom wall projecting outwardly beyond the side walls, tubes mounted on said bottom wall, said tubes having slots disposed longitudinally thereof, tumblers to substantially close said ends 60 and to project beyond said side walls for unrestricted manipulation, said tumblers being journaled on the tubes, each tumbler having an upper and a lower wall integral with each other and an intervening recess, 65 said upper and lower walls having slots to register with the slots of the tubes, a closure bar extending outwardly beyond said side walls and into which the tubes extend, said 70 bar having slots to register with those of the tubes, and a shackle having bits to pass through the various slots to engage the recesses for protective disposition intermediate said upper and lower walls.

In testimony whereof I affix my signature 80 in presence of two witnesses.

JACOB PATOSKA.
